UNITED STATES PATENT OFFICE.

FRED RICKS AND REGINALD BOYD WOODCOCK, OF LEICESTER, ENGLAND, ASSIGNEES
TO UNITED SHOE MACHINERY CORPORATION, OF PATERSON, NEW JERSEY, A COR-
PORATION OF NEW JERSEY.

SEWING MACHINE.

Application filed June 4, 1924, Serial No. 717,769, and in Great Britain June 28, 1923.

This invention relates to bag corner sewing and like operations where the work-piece has to be supported internally on a work-entering horn for the sewing operation.

Typical of such operations are those usually performed by a machine such as is described in the specification of application Serial No. 617,702, filed Feb. 8, 1923, and it is a particular object of the present invention to facilitate the employment of such a machine as last referred to in the sewing of corner seams on leather or other containers with a small opening or of tubular form or with awkward internal corners.

One feature of the invention contemplates the provision in a machine for sewing bag corners of a horn rotatable and cantable which is freely movable to lie in different directions within the workpiece during the sewing and is also of adjustable operative shape so that its shape may be varied in accordance with the requirements of different workpieces or of the different internal corners of the same piece.

Another feature of the invention contemplates the provision of a rotary horn which is freely movable to lie in different directions within the workpiece during the sewing and is provided with a substantially rectilinear work-entering portion that is adjustable about its tip transversely of the direction in which the horn is swung by rotation of the horn, so that it may properly support objects of relatively small dimensions and of tubular or oblong section.

The above and other features of the invention will become fully evident to those skilled in the art from the following description, given by way of example, of one form of the invention.

In the accompanying drawings:—

Figure 1 is a side elevation, partly in section of one form of horn according to the invention applied to a machine of the type shown in the application above referred to.

Figure 2 is a section on the lines 2, 2 of Figure 1;

Figure 3 shows, in plan, the position of the horn when a small bag or case is being sewn along a side edge; and

Figure 4 shows, in elevation, the same bag being sewn at the end.

The invention is shown applied to a lock

stitch sewing machine having the construction and mode of operation of the machine shown and described in Patent No. 473,870, dated April 29, 1892. This machine is provided with stitch forming and work feeding devices fully shown and described in said patent and including a curved hook needle and an awl indicated in Figure 1. The machine is also provided with a work-support 2 having two work supporting faces arranged at right angles to each other and with their line of intersection extending along the line of feed. These surfaces form unyielding external supports for the faces of the work adjoining the corner and the work support and are so mounted that both of these surfaces are at an inclination to the needle path and that this inclination may be varied by adjustment of the support.

In this form of the invention the rotatable and angularly movable roll or tablet 1 which engages the inside of the workpiece and holds it against the external work-support 2 during the operation of the machine is mounted on the ball-shaped end 3 of a comparatively slender rectilinear bar 4 so as to be freely movable angularly about the ball in any direction through an angle of substantially 160° and to be freely rotatable thereon. The bar 4 tapers down towards that end of it on which is the ball. The opposite end of the bar 4 is fixed in a bracket 5 having formed in it a square-section guide-way 6 which is concentric with the ball-shaped end of the bar 4. A plate 7 fixed by screws 8 to the bracket covers the guide-way. The bracket 5 is clamped by a hand-screw 9 to a curved hollow horn 10 (having flats 10° along it to prevent the bracket turning on it) which is concentric with the ball-shaped end of the bar 4 so that by loosening the hand-screw 9 the bracket 5 may be moved, without affecting the position of the work-engaging tablet 1, to substantially any desired position along the horn according to the nature of the workpiece being operated upon, to present the bar 4 in any one of various radial positions on the horn 10 and be then clamped in that position. Collars 11, 11 can be fixed by hand-screws 12, 12 to the horn 10 in various predetermined positions above and below the bracket 5 so that the bar 4 may be quickly moved from one position to another. The horn 10 at its

upper end is fixed in a block 13 which is mounted on the frame of the machine in a manner similar to the horn supporting block described in the aforementioned specification so that the horn may as a whole move vertically and also swing or cant towards and from the external work-support 2 and to either side of the sewing point (indicated at 14 in Figure 3) of the machine as well as 10 rotate about the axis of the pivot pin 15 which axis lies, as will be understood, in the plane of curvature of the horn 10.

There is thus provided a work-supporting horn structure, the shape of which may be 15 varied according to the needs of differing workpieces, and the provision of a rectilinear terminal tablet-supporting bar to said structure admits of the ends being sewn into tubular or oblong section objects of 20 relatively small dimensions.

Having now particularly described and ascertained the nature of our said invention and in what manner the same is to be performed, we declare that what we claim is:

25 1. A sewing machine for sewing bags or like articles having, in combination, means for externally supporting the work with both faces adjacent a corner at an inclination to the needle path, and a rotary and cantable horn that is freely rotatable and cantable to project into the workpiece from different directions during the sewing.

2. A sewing machine for sewing bags or like articles having, in combination, means 35 for externally supporting the work with both faces adjacent a corner at an inclination to the needle path, and a rotary and cantable horn freely movable to project into the workpiece from different directions during the sewing of the same and comprising a substantially rectilinear work-entering portion that is adjustable about the tip of said work-entering portion transversely of the direction in which it is swung by rotation of the horn.

3. A sewing machine for sewing bags or like articles having, in combination, means for externally supporting the work with both faces adjacent a corner at an inclination to the needle path, and a rotary and cantable horn freely movable to project into the workpiece from different directions during the sewing of the same and comprising a work-entering portion that is adjustable 50 about the tip of said work-entering portion transversely of the direction in which it is swung by rotation of the horn.

4. A sewing machine for sewing bags or like articles having, in combination, means 60 for externally supporting the work with both faces adjacent a corner at an inclination to the needle path, and a rotary and cantable horn freely movable to lie in different directions in the workpiece during the 65 sewing of the same and comprising an arcu-

ate rotary member and a work-entering member mounted thereon to be adjustable about the tip of said work-entering portion on said member, the said tip being for that purpose at the center of curvature of the 70 arcuate member.

5. A sewing machine for sewing bags or like articles having, in combination, means for externally supporting the work with both faces adjacent a corner at an inclination to the needle path, and a rotary and cantable horn freely movable to lie in different directions in the workpiece during the sewing of the same and comprising an 75 arcuate member mounted for rotation about an axis passing through the horn tip in the plane of the curvature of the arcuate member, and a work-entering member mounted on the arcuate member for adjustment about the tip of said work-entering member, the 80 said tip being for that purpose at the center of curvature of the arcuate member.

6. A sewing machine for sewing bags or like articles having, in combination, means for externally supporting the work with both faces adjacent a corner at an inclination to the needle path, and a rotary and cantable horn freely movable to lie in different directions in the workpiece during the sewing of the same and comprising an arcuate rotary member, and a work-entering member mounted thereon for adjustment about the tip of said work-entering member and a support above the sewing point in which the horn is mounted and from which 95 it depends.

7. A sewing machine for sewing bags or like articles having, in combination, means for externally supporting the work with both faces adjacent a corner at an inclination to the needle path, and a rotary and cantable horn freely movable to lie in different directions in the workpiece during the sewing of the same and comprising an arcuate rotary member and a work-entering 105 member mounted thereon for adjustment about the tip of the said work-entering member, and stops adjustable on the arcuate member for determining different adjusted positions of the work-entering member.

8. A sewing machine for sewing bags or like articles having, in combination, means for externally supporting the work with both faces adjacent a corner at an inclination to the needle path, and a bag-entering horn mounted for rotary movement about an axis passing through its tip and comprising an arcuate member, the center of curvature of which is at the tip, and a work-entering member mounted thereon for adjustment about the tip of the said work-entering member.

9. A sewing machine for sewing bags or like articles having, in combination, means for externally supporting the work with 130

both faces adjacent a corner at an inclination to the needle path, a bag-entering horn mounted for rotary movement about an axis passing through its tip and comprising an arcuate member, the center of curvature of which is at the tip, a work-entering member mounted thereon for adjustment about the tip of said work-entering member, and a freely swivelling work-supporting tablet at 10 the tip of the horn.

10. A machine for sewing bag corners and the like having a rotary and cantable horn freely rotatable and cantable during the sewing operation to project into the work-15 piece from different directions during the sewing thereof.

11. A machine for sewing bag corners and the like having a work-entering horn comprising a freely rotatable and cantable arcuate member and a work-entering member mounted thereon to be adjustable about the tip of said work-entering member on the 20 said member, the tip being for that purpose

at the center of curvature of the arcuate member.

12. A sewing machine for sewing bags or like articles having in combination, means for externally supporting the work with both faces adjacent a corner at an inclination to the needle path, and a rotary and cantable horn that is freely movable to lie in different directions in the workpiece during the sewing and comprising a work-entering member adjustable to change the operative shape of the horn.

13. A machine for sewing bag corners and the like having a rotary and cantable horn freely movable to lie in different directions within the workpiece during the sewing thereof and provided with a work-entering 40 portion adjustable to change the operative shape of the horn.

In testimony whereof we have signed our names to this specification.

FRED RICKS.

REGINALD BOYD WOODCOCK.
